UNITED STATES PATENT OFFICE.

WILLIAM F. GAMMETER, OF CADIZ, OHIO, ASSIGNOR TO THE W. F. GAMMETER CO., OF CADIZ, OHIO, A CORPORATION OF OHIO.

ROLL.

Application filed May 21, 1926. Serial No. 110,812.

The present invention relates to tubes or hollow metal rolls and has special reference to a roll for use in electric ironing machines, although it is equally applicable to other instances where an accurate inexpensive tube or roll is desired. Great difficulty has been heretofore experienced in obtaining an inexpensive roll which would have a cylindrical surface and at the same time be capable of production at a cost which is not prohibitive, seamless tubing and turned rolls being inaccurate as well as expensive and heavy sheet metal being too hard to be easily formed into a true cylinder. The present invention overcomes these difficulties, and resides in a certain novel construction which is illustrated in the accompanying drawing and will be hereinafter first fully described and then more particularly defined in the appended claims.

In the drawing:

Figure 1 is a perspective view of a tube constructed in accordance with the present invention;

Fig. 2 is an enlarged longitudinal section through one end portion of the tube;

Fig. 3 is a transverse section;

Fig. 4 is a longitudinal section showing a form differing in detail from the form shown in the preceding figures.

According to the present invention, a ply or sheet 1 of thin metal is rolled into a cylindrical form, and then a second ply 2 of like material is rolled into cylindrical form around the first-mentioned ply or sheet with the edges of each sheet or ply forming a butt joint and the joints being preferably diametrically opposed, as indicated at 3 and 4. The plies are then firmly united by spot welding, as indicated at 5, or by seam welding or by the use of rivets, the heads of which are arranged flush with the surfaces of the plies or laminations. I also provide heads 6, one of which is employed at each end of the roll, and intermediate braces 7 which are of the same form as the heads and are disposed at intermediate points in the length of the roll. Each head or brace may be stamped from heavy sheet metal or may be a turned casting and comprises a body or disk portion 8 having a central opening or a hub member 9 in which a driving shaft may be inserted and secured in any convenient or preferred

manner. The edge portion of the disk is formed into a rim or annular flange 10 adapted to fit snugly within the inner cylindrical sheet, ply or lamination of the roll. After the tube has been formed by wrapping the sheets or plies 1 and 2 into cylindrical form, as described and shown, the braces and heads are forced into the tube and are firmly secured by spot welding, as indicated at 11, riveting or otherwise. A light and strong roll is thus produced, and it has been found that by employing the laminated cylindrical shell and forcing the circular heads and braces into the same an extremely accurate roll is attained at a cost which will permit the sale of the roll profitably at a low price.

In Fig. 4, the outer ply 2 and the head 6 are the same as in Figs. 1, 2 and 3. The inner ply, 12, however, is not plain but is corrugated, as shown at 13, the corrugations extending circumferentially and a smooth plain portion being left at each end of the ply to fit between the rim of the head and the end of the outer ply or shell, as shown at 14.

Having thus described the invention, I claim:

1. A tube for rolls consisting of two coterminous plies of thin sheet material each rolled into cylindrical form with its edges meeting to form a joint, the joints being spaced apart circumferentially of the tube and the two plies of sheet material having their opposed surfaces in contact.

2. A roll consisting of two plies of thin sheet material each rolled into cylindrical form with its edges meeting to form a joint and the joints spaced circumferentially of the roll, the inner ply having circumferentially extending corrugations.

3. A roll consisting of a shell composed of two coterminous plies of thin sheet material each rolled into cylindrical form with its edges meeting to form a joint and the joints disposed at circumferentially spaced points of the shell, circular disks fitted into the ends of the inner tube of the shell and having rim members snugly fitting within and supporting the shell, the rim members and overlying portions of the tubes being firmly secured together.

In testimony whereof I affix my signature.

WILLIAM F. GAMMETER.
